UNITED STATES PATENT OFFICE

ETEOCLE PASQUALI, OF FREEPORT, NEW YORK

ANTISKID APPLIANCE FOR SHOES

Application filed December 9, 1931. Serial No. 579,960.

This invention appertains to new and useful improvements in anti-skid attachments for shoes, and the same is an improvement on my co-pending application, Serial No. 556,637, filed August 12, 1931.

An important object of the invention is to provide an anti-skid device for shoes which is especially adapted for use in the playing of golf, hiking or on icy footing.

Another important object of the invention is to provide an anti-skid attachment for shoes which can be readily applied and detached in a quick and convenient manner.

Other important objects and advantages of the invention will become apparent to the reader of the following specification.

In the drawings:

Figure 1 represents a side elevational view of the shoe with the attachments thereon.

Fig. 2 represents a bottom plan view of the shoe with the attachment in place thereon.

Fig. 3 represents a top plan view of one of the calks.

Fig. 4 represents a side elevational view of the calk shown in Fig. 3.

Fig. 5 represents a plan view of the heel attachment fastening unit.

Fig. 6 represents a side elevational view of the unit shown in Fig. 5.

Fig. 7 is a fragmentary detailed sectional view showing the fastening unit of Fig. 5 in closed position.

Fig. 8 represents a plan view of the fastening unit for the sole device shown in Fig. 2 in open position.

Fig. 9 represents a side elevational view of the fastener shown in Fig. 8.

Fig. 10 is an end elevational view of the fastener shown in Fig. 8.

Fig. 11 is a perspective view of a special type of link.

Fig. 12 represents a plan view of a calk assembly used in complement with the fastener in Fig. 8.

Fig. 13 represents a side elevational view of the assembly shown in Fig. 12.

Fig. 14 represents an outside elevational view of the assembly shown in Fig. 12.

Fig. 15 represents a top plan view of the calk assembly which is employed in complement with the fastener shown in Fig. 5.

Fig. 16 represents an outer side elevational view of the assembly shown in Fig. 15. 55

Fig. 17 represents a side elevational view of the assembly disclosed in Fig. 15.

Fig. 18 represents a side elevational view of one of the single calk members.

Fig. 19 represents a vertical sectional view 60 through one of the calk members.

Referring to the drawings wherein like numerals designate like parts, it can be seen in Fig. 1, that numeral 5 represents a shoe upper, while numerals 6 and 7 represent the 65 sole and heel portions thereof.

For the sole, the calk and fastener assemblies 8 and 9 respectively are employed in complement with each other and in connection with the single calks 10—10 which are 70 at the toe portion of the shoe.

As is clearly apparent in Figs. 18 and 19, it can be seen that the single calk 10, each includes an outstanding ground engaging 75 protuberance 11 of hollow construction, and the calk is otherwise provided with a hook-shaped extension 12 which is engageable over the edge portion of the sole 6 as in the manner substantially shown in Figs. 1 and 2.

Diametrically opposite from the hook 12 is a lug extension 13 having an opening 14 therein for receiving one of the links 15. Each of these links consists of an elongated metallic strap of spring material, split and having its ends slightly spaced apart and with one end portion gradually reduced as at 16 to permit ready flexibility when engaging the same with any one of the fasteners, assemblies, or calks. 80

Two additional single calks 17—18, are 90 each provided with an outstanding protuberance 19 and with three laterally disposed tongs 20, each provided with an opening 21. As is clearly shown in Fig. 2, one of the links 15 is interposed between each of the calks 10—10, and the single calks 18 while the calks 17—18 are connected by an additional link 15. 95

The assembly 8 is connected to the calk 17 by a link 15 while the fastening unit 9 is 100 connected to the calk 17 by a link 15.

The calk assembly 8 includes a plate 22 having a slot 23 therein and suitable weight reducing openings 24 therein. At each end of this plate 22, is a calk 25 similar in construction to the aforementioned calk, and each provided with a sole edge engaging hook 26. Each of these calks 25 is equipped with the outstanding protuberance 27 for ground engagement.

- 10 The fastener units 9 consist of a U-shaped plate 28 having a calk 29 at each end of its bight portion, each calk being equipped with the outstanding protuberance 30 for ground engagement. The leg portions *a-a* of this 15 U-shaped plate are each provided with a hinge barrel *b* in its outer end for receiving the corresponding trunnions 31 of the lever 32. In this manner, the lever is swingably connected to the U-shaped plate and is preferably of some suitable spring material offset adjacent its outer end as at 33 to provide a shoulder from which the tab 34 extends.

Obviously, with one of the links 15 engaged through the slot 35, of the lever 32, the other links will serve to draw the calks 10-10 and calk assembly 8 as well as the hook 36 on the plate 28 snugly against the edge portion of the shoe sole as the lever 32 is swung downwardly upon the plate 28. To maintain the 25 prongs in this clamped position, with respect to the shoe sole, the lever 32 is forced downward upon the plate 28 (see Figures 8 and 9) so that the shoulder 33 will engage behind the rib 37 and will thus remain in place until 30 separation by the exertion of pressure against the tab 34.

In describing the anti-skid attachment for the heel, it will be found that numeral 38 represents the forward calk assembly, while 40 numeral 39 generally refers to the rear calk assembly which also involves the fastening means for clamping both assemblies to the heel.

The assembly 38 consists of three calk 45 members 39, 40 and 41, the calk members 39 and 40 being connected to the calk 41 by the reinforced bars 42-42. The calk members 39 and 40 are equipped with hooks 43 for engagement with the heel, while the calk 50 member 41 is provided with a tongue 44 having a slot 45 therein for receiving one of the aforementioned link members 15. The aforementioned calks 39, 40 and 41 are each provided with a ground engaging pro- 55 tuberance 46.

The calk assembly and fastener 39 consists of a substantially U-shaped plate 47 having a calk 48 at each end of its bight portion, each calk being provided with a 60 ground engaging protuberance 49 and also with an obliquely disposed hook member 50 for engagement with the curved rear portion of the shoe heel 7.

The leg portions *C-C* of the plate 47, is 65 provided with hinge barrels *e-e* for receiv-

ing the trunnions 51-51 of the lever 52. The lever 52 is of spring material, is offset as at 70 53, and at this point, the same is provided with a pair of oppositely disposed lateral arms 54-54 for engagement over the ribs 55-55 on the plate 47. Numeral 56 represents a finger engageable lift, whereby this lever can be removed from this retained position. It can be seen, that with a link 57 75 passing thru the opening 58 in the lever 52, and also through the opening 45 in the prong 44 of the assembly 38, downward pressure of the lever 52 onto the plate 47 to secure the lever in the position aforementioned, will result in the contraction of these calk assemblies in clamping position on the heel 7.

While the foregoing specification sets forth the invention in specific terms, it is to be understood that numerous changes in the shape, size and materials may be resorted to 80 without departing from the spirit and scope of the invention as claimed hereinafter.

Having thus described my invention, what I claim as new is:-

1. An anti-skid device for shoes comprising a pair of calk assemblies, each calk assembly being provided with a sole edge engaging hook, one of said assemblies being provided with a swingable spring lever having a shoulder thereon, a rib on the complementary assembly behind which the shoulder can tensionally engage, and a link member between the lever and the remaining calk assembly.

2. An anti-skid device for shoes comprising a pair of calk assemblies, each calk assembly being provided with a sole edge engaging hook, one of said assemblies being provided with a swingable spring lever having a shoulder thereon, a rib on the complementary assembly behind which the shoulder can tensionally engage, a link member between the lever and the remaining calk assembly, said link member consisting of a link-like member split and having one end 100 portion reduced toward its extremity.

3. An anti-skid device for shoes comprising a pair of calk assemblies, each calk assembly being provided with a sole edge engaging hook, one of said assemblies being provided with a swingable spring lever having a shoulder thereon, a rib on the complementary assembly behind which the shoulder can tensionally engage, a link member between the lever and the remaining calk assembly, said assembly with the lever thereon comprising a U-shaped plate having its leg portions provided with hinge barrels at their ends, and trunnions on the said lever for engagement into the said hinge barrels.

In testimony whereof I affix my signature.

ETEOCLE PASQUALI.
